UNITED STATES PATENT OFFICE

134,290.

DESIGN FOR A PAIR OF SUNGLASSES OR THE LIKE

Arthur Ditto, Roslindale, Mass., assignor to Marine Optical Mfg. Co., Roslindale, Mass., a corporation of Massachusetts

Application February 18, 1942, Serial No. 105,883

Term of patent 14 years

To all whom it may concern:

Be it known that I, Arthur Ditto, a citizen of the United States, residing at Roslindale, in the county of Suffolk and State of Massachusetts, have invented a new, original, and ornamental Design for a Pair of Sunglasses or the like, of which the following is a specification, reference being had to the accompanying drawing, forming part thereof.

Fig. 1 is a front view of a pair of sunglasses or the like showing my new design; and

Fig. 2 is a plan view thereof, the temples being shown in fragmentary condition for convenience of illustration.

I claim:

The ornamental design for a pair of sunglasses or the like, substantially as shown.

ARTHUR DITTO.
